BRAKE SHOE GRINDER AND GAUGE

Hjalmar Thomason, Los Angeles, Calif.

Application October 3, 1934, Serial No. 746,665
Renewed November 28, 1936

17 Claims. (Cl. 51—241)

This invention relates to improvements in brake shoe grinders and gauges.

An object of the invention is to provide a device for grinding brake shoes, such as those used upon automobiles, so as to render them truly round to conform to the surface of the brake drum with which the brake shoes are designed to engage.

More specifically, an object of the invention is to provide a brake shoe grinder which is of such design as to enable its application to any conventional axle, axle housing, or spindle, so that the same brake shoe grinder may be used to grind the brake shoes of a vehicle regardless of the design of its axle, axle housing, or spindle.

Another object of the invention is to provide a brake shoe grinder having a clamping mechanism adapted to be applied either to an axle, an axle housing, or spindle having a grinding apparatus adjustably mounted thereon, the design being such that the grinding apparatus may be moved inwardly toward the center of rotation of the brake drum against adjustable limits which limit the depth to which the grinding apparatus may

grind the brake shoes.

A further object of the invention is to provide a brake shoe grinder consisting essentially of a clamping mechanism for clamping the apparatus upon an axle, spindle, or axle housing, and which has the grinding apparatus removably positioned thereon so that the grinding mechanism can be removed while the construction is being set up or mounted. To this end a gauge bar may be mounted on the construction for gauging the position of the grinding apparatus, thus enabling the grinding mechanism, because of its weight, to be properly set, after which the grinding apparatus may be reinstalled.

Another object of the invention is to provide a brake shoe grinder having a clamping mechanism of such design that a micrometer or other length measuring instrument may be applied thereto indicating the diameter of the brake drum and thus enabling an accurate setting of the limiting stops which limit the inward movement of the grinder during its grinding of the brake shoes.

With the foregoing and other objects in view, which will be made manifest in the following detailed description, and specifically pointed out in the appended claims, reference is had to the accompanying drawings for an illustrative embodiment of the invention, wherein:

Fig. 1 is a view in side elevation, parts being broken away and shown in vertical section illus-

trating the improved brake shoe grinder and gauge.

Fig. 2 is a sectional view taken substantially upon the line 2—2 upon Fig. 1.

Fig. 3 is a sectional view taken substantially upon the line 3—3 upon Fig. 1.

Referring to the accompanying drawings, wherein similar reference characters designate similar parts throughout, I have illustrated the improved brake shoe grinder and gauge as having been applied to an axle A having a tapered end. The device consists of a clamping mechanism adapted to be applied to the axle. This comprises a forward pair of clamping blocks 10 and 11 (see Fig. 3), and a rear pair of clamping blocks 12 and 13. As shown on Fig. 3, the forward pair of clamping blocks have their opposed faces notched, as indicated at 14, with relatively shallow notches, whereas the outer sides of these clamping blocks are provided with relatively deep, wide notches 15. In a similar way the rear pair of clamping blocks have opposed faces provided with narrow or shallow notches 16 and outer notches or recesses 17, which are relatively deep and broad. These clamping blocks are swiveled or rotatably mounted on vertical standards. The standards for the forward pair consist of two upper members 18 and 19 having at their lower ends cylindrical extensions 20 which extend down through the clamping blocks and into lower members 21 and 22. Tapered pins 23 are driven through the lower members and through the extensions 20, serving to connect the upper and lower members of each standard together. By this construction the clamping blocks can be rotated so that their opposed faces will present the narrow notches 14 for application to an axle of relatively small diameter or in applying the construction to an axle or axle housing of relatively large diameter these clamping blocks can be turned so as to have the outer broad notches 15 opposite one another.

The rear clamping blocks are mounted on standards 24 and 25 which are duplicates of the standards for the forward blocks. At the tops and bottoms of the standards there are transverse cross members, the cross members for the forward pair being indicated at 27 and 28. These standards are provided with extensions at their tops and bottoms indicated at 29 and 30 which are slidable in slots 31 and 32 in the cross members. As a means for holding the standards and cross members together the tops and bottoms of the standards are provided with nuts and washers indicated at 33.

To effect a horizontal adjustment of the standards and the clamping blocks thereon the upper parts of the forward standards indicated at 18 and 19 have a screw provided with right and left hand threads and indicated at 34 extending therethrough. In a similar way the lower parts 21 and 22 have a right and left handed screw 35 extending therethrough. These screws 34 and 35 are provided at each end with knurled handles 36 and in order to cause the screws to be turned in unison each screw is provided at one end with a small sprocket, the sprockets being indicated at 37 and 38. And endless chain 39 passes over both sprockets and the sprockets and chain are enclosed within a cover 40 which connects the top and bottom cross members 27 and 28. By this construction on turning any one of the four handles 36 which are associated with the forward pair of clamping blocks the tops and bottoms of 15 the respective standards will be caused to move 20 toward or away from each other in unison.

The standards 24 and 25 of the rear pair of clamping blocks are similarly provided with two screws 41 and 42 having handles 43 and with corresponding sprockets and an endless chain so that when one of the four handles 43 associated with the rear pair of clamping blocks are turned the standards for the rear pair of clamping blocks will be moved toward or away from each other 30 in unison. There is no connection between the screws of the forward pair of clamping blocks and the screws of the rear pair of clamping blocks so that it is possible to adjust the rear pair of clamping blocks independently of the forward pair in applying the construction to an axle having a tapered end as shown on Fig. 1. By virtue of the rotatable mounting for the clamping blocks not only is it possible to reverse the positions of the blocks for various sized axles or spindles but 40 the clamping blocks themselves may accommodate themselves to the axle. If the axle has an abrupt taper these clamping blocks will seat themselves accordingly. On the other hand, if the axle or axle housing should be straight, as distinguished from tapered, the clamping blocks 45 will seat themselves accordingly.

The forward and rear cross members are connected in a longitudinal direction by means of tubular bars 44 and 45 and the cross members are secured in adjusted position thereon by means of set screws 46. In this way the distance between the forward set of clamping blocks and the rear set of clamping blocks can be adjusted for various axles or spindles. These tubular members also extend through transverse members 47 and 48 which are held in adjusted position thereon by means of set screws 49. These transverse members have at their outer ends slotted sleeves indicated at 50, 51, 52, and 53. Standards for the grinding apparatus indicated at 54 and 55 slidably extend therethrough. The upper sleeves 50 and 51 are provided with tightening screws 56 which serve to tighten these sleeves about the standards to take up wear. 60 They are not tightened sufficiently to cause the sleeves to clamp tightly upon the standards. Below the lower transverse member 48 there is a yoke 57 having split sleeves 58 at its ends surrounding the standards 54 and 55. These split sleeves are tightened by means of screws 59 which can be tightened so as to clamp the yoke upon the lower ends of the standards 54 and 55. A screw 60 is threaded through the center of the yoke and has its upper end 61 swiveled in the 70 bottom of the lower transverse member 48. By 75

this construction, when the clamping members or clamping blocks are closed against the axle A, on turning screw 60, standards 54 and 55 can be raised or lowered and caused to slide through the sleeves 50, 51, 52 and 53. The tops of sleeves 50 and 51 are carefully milled so as to be even with each other and adjustable collars 62 and 63 are disposed about the standards above these sleeves. These collars can be set in adjusted position by means of set screws 64. The tops of the standards support a saddle 65 having T-shaped slots 66 in its sides and serving to support the motor 67 of the grinding apparatus. This motor carries bolts on its sides indicated at 68 which are capable of passing through the entrances to the T-shaped slots so as to permit the grinding apparatus to be removed from the saddle as an entirety or the motor when in applied position can be adjusted forward or backward by loosening and tightening these bolts 68. The rotor of the motor carries an abrasive element and for this purpose I prefer to employ replaceable rubber sleeves 69 which carry the abrasive. The sleeve is surrounded by a shroud 70 having an outlet 71 on top of the motor leading through a 25 swivel 72 to a hose 73 leading to a vacuum pump or fan. The purpose of producing the vacuum is to cause the grindings to be withdrawn through the outlet 71. The swivel also enables the entire apparatus to be turned without twisting the hose 30 73 or the electric cable 74 which supplies the electric current to the motor.

The upper tubular bar 44 carries an extension 15 which provides a socket for the reception of an arm 76 on the micrometer 77, the purpose of 25 which will be hereinafter described. On the sides of the saddle there are provided ears 78, one of which has a set screw 79 for adjustably mounting a gauge bar 80. This gauge bar may be removed when the grinding apparatus is installed 40 in the saddle and may be applied on removal of the grinder to assist in setting the apparatus. The bottom surface of the gauge bar is either a distance from the center of the axle A equal to the distance that the bottom of sleeve 69 is from 45 the center of the axle or a distance equal to that which the bottom of the sleeve 69 is from the center of the axle plus a small predetermined increment such as .015 of an inch.

The operations and advantages of the improved 50 brake shoe grinder and gauge are as follows: To apply the construction the micrometer 77 is first adjusted so as to measure the diameter of the brake drum. The micrometer forms no part of the present invention, and therefore, its details 55 of construction have not been disclosed herein. It should, however, be such that on adjustment its ends will simultaneously move toward or away from its center. When the brake drum has been measured the micrometer has its arm 76 inserted 60 in the socket of extension 15 and by swinging the micrometer about its arm 76 as a center the high point of the arc circumscribed by the top of the micrometer can be easily ascertained. This high point will be a distance from the center of the 65 axle A equal to the radius of the drum. After the motor or grinding apparatus is in applied position this is adjusted by means of screw 60 until the bottom of sleeve 69 is just tangent to the arc described by the top of the micrometer. When in 70 this position collars 62 and 63 are set so that they will be touching the tops of sleeves 50 and 51. When the position of the grinder has thus been set the screw 60 is caused to elevate the standards 75 so that the grinder will be slightly above the ra-

dius to which it is desired to grind the brake shoes, in which case there will be a small clearance in the bottoms of the collars and the tops of the sleeves 50 and 51, as shown on Figs. 1 and 2.

- 5 The micrometer 77 is then removed and the construction is ready to apply to axle A. Set screws 48 are loosened and the transverse members for the front and rear clamping blocks are adjusted along the lengths of tubular bars 44 and 45 so as to 10 properly position the front pair of clamping blocks and the rear pair of clamping blocks with respect to the particular axle or spindle. The device is then shifted on to the axle or spindle and by rotating the handles for the various screws the clamping blocks may be caused to engage the sides of the axle and accommodate themselves thereto. In some instances it may be necessary to apply the bolt on the end of the axle to its outer end together with its washer so that the rear pair of 15 clamping blocks will have a shoulder on the axle against which they may bear, thus preventing the clamping mechanism from loosening on the tapered axle during rotation. The device is then ready to proceed with the grinding.

25 With the grinder in elevated position, that is, slightly above the limit determined by the set collars 62 and 63, a cut is taken on the brake shoes surrounding the axle. This grinding action continues while the standards 54 and 55 are gradually lowered by means of screw 60 until the collars 62 and 63 engage the tops of sleeves 50 and 51 at which time the grinding is completed. When completed the brake drum engaging surfaces of the shoes will be ground in conformity to the 30 brake drum, after which the apparatus is removed from the axle.

Because of the fact that the motor of the grinding apparatus is quite heavy it is frequently desirable to take off the grinding apparatus while 40 the mechanism is being clamped upon the axle and while it is being set. This can be easily accomplished and when the grinding apparatus is removed the gauge bar 80 is installed. The bottom surface of the gauge bar is preferably a 45 distance from the center of the axle A equal to the distance that the bottom of sleeve 69 is from the center of the axle plus a predetermined increment, such as, for example, .015 inch. Consequently, by knowing this slight increment the bottom surface of the gauge bar may be used as 50 a gauge for gauging the positions to which the collars 62 and 63 shall be set just as well as the bottom surface of sleeve 69. When the gauge bar has been used to facilitate setting of the apparatus it may be removed and upon application of the 55 grinding apparatus to the saddle it will be properly positioned.

Various changes may be made in the details of construction without departing from the spirit or 60 scope of the invention as defined by the appended claims.

I claim:

1. A brake shoe grinder comprising, in combination, motor driven grinding means, clamping means adjustably connected thereto and adapted to be clamped upon an axle or spindle so as to swing the grinding means about the axle or spindle as a center, said clamping means including swiveled axle or spindle engaging blocks whereby the blocks may accommodate themselves to straight or tapered axles and spindles.

2. A brake shoe grinder comprising, in combination, motor driven grinding means, clamping means adjustably connected thereto and adapted 75 to be clamped upon an axle or spindle so as to

swing the grinding means about the axle or spindle as a center, said clamping means including swiveled axle or spindle engaging blocks whereby the blocks may accommodate themselves to straight or tapered axles and spindles, each block having a plurality of differently sized engaging faces whereby on swiveling the blocks about, the blocks may be caused to engage differently sized axles and spindles.

3. A brake shoe grinder comprising a motor driven grinding means, standards connected thereto, and a clamping means adapted to be clamped about an axle or spindle slidably mounted upon the standards, said clamping means including opposed axle or spindle engaging blocks, and means for forcing the blocks toward each other.

4. A brake shoe grinder comprising a motor driven grinding means, standards connected thereto, a clamping means adapted to be clamped about an axle or spindle slidably mounted upon the standards, said clamping means including opposed axle or spindle engaging blocks rotatably mounted so as to accommodate themselves to straight or tapered axles or spindles, and means for forcing the blocks toward each other.

5. A brake shoe grinder comprising a motor driven grinding means, standards connected thereto, and a clamping means adapted to be clamped about an axle or spindle slidably mounted upon the standards, said clamping means including a forward pair of opposed spindle or axle engaging blocks, and a rear pair of opposed spindle or axle engaging blocks, and means for forcing the blocks of each pair toward each other independently of the blocks of the other pair.

6. A brake shoe grinder comprising a motor driven grinding means, standards connected thereto, a clamping means adapted to be clamped about an axle or spindle slidably mounted upon the standards, said clamping means including a forward pair of opposed spindle or axle engaging blocks, and a rear pair of opposed spindle or axle engaging blocks, and means for forcing the blocks of each pair toward each other independently of the blocks of the other pair, said blocks being mounted for rotational movement.

7. A brake shoe grinder comprising a motor driven grinding means, standards connected thereto, a clamping means adapted to be clamped about an axle or spindle slidably mounted upon the standards, said clamping means including a forward pair of opposed spindle or axle engaging blocks, and a rear pair of opposed spindle or axle engaging blocks, means for forcing the blocks of each pair toward each other independently of the blocks of the other pair, and means for adjusting the blocks of one pair toward or away from the blocks of the other pair.

8. A brake shoe grinder comprising a forward clamping means, a rear clamping means, means adjustably connecting the forward clamping means and the rear clamping means together, cross members on the connecting means, standards slidable on the cross members, a saddle on the standards, motor driven grinding means removably mounted upon the saddle, and settable collars on the standards engageable with one of the cross members to limit inward movement of the grinding means with respect to the clamping means.

9. A brake shoe grinder comprising a forward clamping means, a rear clamping means, means adjustably connecting the forward clamping

- means and the rear clamping means together, cross members on the connecting means, standards slidable on the cross members, a saddle on the standards, motor driven grinding means removably mounted upon the saddle, and screw means associated with one of the cross members for advancing or retarding the grinding means toward or away from the clamping means.
10. A brake shoe grinder comprising a forward clamping means, a rear clamping means, means adjustably connecting the forward clamping means and the rear clamping means together, cross members on the connecting means, standards slidable on the cross members, a saddle on the standards, motor driven grinding means removably mounted upon the saddle, and a gauge bar removably mounted upon the saddle for gauging the position of the grinding means when the grinding means is removed from the saddle.
15. 11. A brake shoe grinder, comprising in combination a motor driven grinding means, a clamping means adapted to be clamped upon an axle or spindle, an adjustable supporting and connecting means connected between the clamping and the grinding means and operative to vary the radial distance between the axis of the axle or spindle and the grinding means, a settable means associated with the adjustable supporting and connecting means and serving to limit the inward movement of the grinding means to the radius to which the brake shoes are to be ground, the grinding means being adapted to swing on the axle or spindle as a center, the adjustable supporting and connecting means being adapted to initially position the grinding means at a greater radius from the axis of the axle or spindle than that defined by the said settable means, whereby the brake shoes may have their outside peripheral portions ground until the limit defined by the settable means.
20. 12. A brake shoe gauge comprising a rigid structure forming a standard adapted to straddle an axle or a spindle, a gauge bar adjustably mounted on the standard, a supporting means connected to the standard, a plurality of pairs of blocks having seating surfaces, each rotatably mounted on a part of the said supporting means, an adjusting device for the said supporting structure to clamp the blocks to an axle or a spindle, the blocks being adapted to rotate to accommodate themselves to straight or tapering axles and spindles.
25. 13. A brake shoe gauge comprising a first rigid standard adapted to straddle an axle or a spindle, secondary standards adjustable on the first mentioned standard, rotatable clamping blocks mounted on the second standard and arranged in pairs, the blocks having complementary faces to engage opposite sides of an axle or spindle and

being adapted to adjust themselves to straight or tapered axles or spindles, a gauge bar adjustably mounted on the first standard, means to adjust the second standards relative to the first standard to position the gauge bar parallel to the axis 5 of the axle or spindle.

14. In a brake shoe gauge comprising a plurality of pairs of shafts forming secondary standards, each of the shafts having a rotatable clamping block thereon, said blocks having complementary faces to engage the opposite sides of an axle or spindle and by their rotation accommodate themselves to a straight or tapered axle or spindle, means to simultaneously adjust opposite ends of the said shafts forming the standards to clamp the blocks to an axle or spindle, a gauge bar, a supporting means therefor operatively connected to the secondary standards and having means for adjusting the gauge bar radially 10 in respect to the axle or spindle clamped by the 15 said blocks.

15. A brake shoe gauge comprising in combination a plurality of pairs of secondary standards, each having a cylindrical portion with a rotatable clamping block thereon, each pair of blocks having complementary surfaces, means to adjust each pair of standards to clamp the blocks thereof on an axle or spindle, each pair of blocks by its rotation being adapted to accommodate themselves to straight or tapered axles or 20 spindles, a cross member adjustably connected to each of the secondary standards and primary standards adjustable on the cross members and having a gauge bar thereon whereby the gauge bar may be adjusted radially and parallel to the 25 axis of the axle or spindle clamped by the 30 said blocks.

16. A device of the class described comprising a gauge bar, standards connected thereto, and a clamping means adapted to be clamped about 40 an axle or spindle slidably mounted upon the standards, said clamping means including two opposed pair of axle or spindle-engaging blocks, and means for forcing the blocks of each pair toward each other independently of the blocks 45 of the other pair.

17. A device of the class described comprising a pair of standards on which a gauge bar or a grinder may be mounted, clamping means adapted to be clamped about an axle or spindle slidably mounted upon the standards, and means for mounting a micrometer adapted to measure the diameter of a brake drum on the clamping means in such a manner that the center of the diameter measured by the micrometer may be positioned 50 coincident with the axis of the axle or spindle about which the clamping means is adapted to be 55 clamped.

HJALMAR THOMASON.
